COOLING UNIT

Harold A. Greenwald, Detroit, Mich., assignor, by
mesne assignments, to Kelvinator Corporation,
Detroit, Mich., a corporation of Michigan

Application June 15, 1931, Serial No. 544,667

6 Claims. (Cl. 62—126)

This invention relates generally to refrigerating apparatus, particularly to the cooling units thereof, and consists of certain novel features of construction, combinations and arrangements 5 of parts that will be hereinafter more fully described and particularly pointed out in the appended claims.

In the accompanying drawings:

Figure 1 is a diagrammatic view of a refrigerating apparatus of the high side flooded type 10 and showing a cooling unit embodying my invention as a part thereof;

Figure 2 is a front elevation of the cooling unit illustrated in Figure 1;

15 Figure 3 is a vertical sectional view through the cooling unit;

Figure 4 is a diagrammatic view of refrigerating apparatus of the expansion valve type;

20 Figure 5 is a front elevation of the cooling unit illustrated in Figure 4;

Figure 6 is a vertical sectional view through the cooling unit illustrated in Figure 5.

Referring to Figures 1 to 3 inclusive wherein refrigerating apparatus of the high side flooded type is illustrated, A is a cooling unit embodying 25 my invention; B is a float chamber; C is a compressor, and D is a condenser, all being connected together by suitable tubing and forming a closed circuit for the refrigerant. As shown, the unit 30 A projects forwardly from an upright panel E and has a body 1 comprising concentric sheet metal shells 2 and 3. Preferably these shells 2 and 3 are corrugated and are secured together at their opposite ends. In the present instance 35 the inner shell 2 is provided at its opposite ends with laterally projecting flanges 4 and 5 respectively of substantially L cross section, while the outer shell 3 is sleeved upon and is welded to the bases 6 and 7 respectively of said flanges. Thus 40 a chamber F is provided between the shells for the reception of the refrigerant and the corrugations 8 afford the proper strength and rigidity to resist deformation due to the pressure of the refrigerant.

45 Referring to Figures 4 to 6 inclusive wherein refrigerating apparatus of the expansion valve type is illustrated, A' is the cooling unit embodying my invention; B' is the expansion valve; C' is the compressor, and D' is the condenser, all 50 being connected by suitable tubing to form a closed circuit. In this instance the unit A' is the same as A illustrated in Figures 1 to 3 except that brine instead of refrigerant is within the chamber F' and expansion coils 10 for the refrigerant encircle the inner shell 2' and are con-

nected by suitable tubing 11 to the compressor C' and condenser D'. Thus in this construction the expansion coils 10 carry the pressure of the refrigerant, and the corrugations 8' provide the required amount of heat absorption surface in a 60 relatively small space.

From the foregoing it will be apparent that the bodies 1 and 1' respectively of the units A and A' are identical and may be made by the same set of tools. When used in the expansion valve 65 system the corrugated shells of the body provide the proper heat absorption surface in a small space, and when used in the flooded type system such corrugations also provide the proper strength and rigidity to resist deformation due to the pressure of the refrigerant. In both constructions the inner shell constitutes a support and housing for the ice trays or receptacles containing fluids to be frozen. It will be noted that the material of the inner shell is relatively wide between the 70 corrugations, wider than the corrugations, so as to provide a large flat heat absorbing surface for the ice tray or trays supported thereon.

While it is believed that from the foregoing description the nature and advantages of the 80 invention will be readily apparent, I desire to have it understood that I do not limit myself to what is herein shown or described and that such changes may be resorted to when desired as fall within the scope of what is claimed. 85

What I claim as my invention is:

1. An evaporator for a refrigerating system, comprising in combination, a plurality of concentric shells joined at either ends with the intermediate portions thereof spaced from one another 90 to provide a closed chamber for a refrigerating medium, the inner of said shells having narrow downwardly extending corrugations at the bottom thereof and the material between said corrugations being wider than said corrugations to 95 provide a large heat absorbing surface for supporting an ice tray.

2. An evaporator for a refrigerating system, comprising in combination, a plurality of concentric shells joined at either ends with the intermediate portions thereof spaced from one another to provide a closed chamber for a refrigerating medium, the inner of said shells having narrow downwardly extending corrugations at the bottom thereof and the material between said corrugations being wider than said corrugations to 100 provide a large heat absorbing surface for supporting an ice tray, and refrigerant conveying tubes in intimate metallic contact with the said material. 110

3. An evaporator for a refrigerating system, comprising in combination, a plurality of concentric shells joined at either ends with the intermediate portions thereof spaced from one another 5 to provide a closed chamber for liquid refrigerant, the inner of said shells having downwardly extending corrugations at the bottom thereof projecting into the liquid refrigerant and the material between said corrugations being wider than said corrugations to provide a large heat absorbing surface for supporting an ice tray. 10
4. An evaporator for a refrigerating system, comprising in combination, a plurality of concentric shells joined at either ends with the intermediate portions thereof spaced from one another 15 to provide a closed chamber for a refrigerating medium, the inner of said shells having corrugations projecting outwardly into the refrigerating medium and the corrugations at the bottom being narrower than the material between adjacent corrugations, said material between the corrugations providing a large flat heat absorbing surface for supporting an ice tray. 20
5. In a refrigerating system, an evaporator providing a large heat absorbing surface for supporting an ice tray and outwardly extending heat 25
- absorbing surface for cooling circulating air, comprising in combination, a pair of concentric shells joined at either ends with the intermediate portions thereof spaced from one another to provide a closed chamber for a refrigerating medium, the intermediate portions of said shells having aligned outwardly projecting heat absorbing corrugations and refrigerant conveying tubes in intimate metallic contact with the material between the corrugation of the inner shell. 80
6. In a refrigerating system, an evaporator providing a large heat absorbing surface for supporting an ice tray and outwardly extending heat absorbing surface for cooling circulating air, comprising in combination, a pair of concentric shells joined at either ends with the intermediate portions thereof spaced from one another to provide a closed chamber for a refrigerating medium, the intermediate portions of said shells having sharp outwardly projecting fin like heat absorbing corrugations and having flat ice tray supporting portions intermediate said corrugations, said shells having upwardly extending side walls and the corrugations of said side walls extending upwardly. 90
